UNITED STATES PATENT OFFICE.

EDUARD FRIEH AND RUDOLF NÖLLENBURG, OF NORDHAUSEN, GERMANY,
ASSIGNORS TO DEUTSCHE TIEFBOHR - AKTIEN - GESELLSCHAFT, OF
NORDHAUSEN, GERMANY, A CORPORATION.

SHAFT-BORING APPARATUS.

No. 836,494.

Specification of Letters Patent.

Patented Nov. 20, 1906.

Application filed October 14, 1903. Serial No. 177,039.

To all whom it may concern:

Be it known that we, EDUARD FRIEH, whose post-office address is No. 18 Erfurterstrasse, and RUDOLF NÖLLENBURG, whose post-office address is No. 13 Rothenburgerstrasse, Nordhausen, Kingdom of Prussia, German Empire, subjects of the King of Prussia, German Emperor, have invented a new and useful Shaft-Boring Apparatus, of which the following is a specification.

The several forms of percussion shaft-boring apparatus at present employed for soil containing a large amount of water, but not quicksand, are operated from the surface of the ground by being raised and lowered by means of rods or cables whether the work is performed by a single large drill or for the purpose of reducing the weight by a group of small drills mounted in a fixed frame. The momentum to be overcome in raising the drills requires considerable non-productive expenditure of power and disadvantageously limits the number of strokes. The great blow results, under the present circumstances, in large losses in friction and water at the wall of the shaft, which in view of the large masses employed is of great disadvantage.

The present invention obviates the above drawbacks and greatly increases the efficiency of the boring by the arrangement within a revoluble air-tight casing of a group of automatic drills, each of which is operated independently from a point in proximity to its point of application.

The invention is illustrated in the annexed drawings, in which—

Figure 1 is a sectional elevation of a boring apparatus constructed in accordance with my invention. Fig. 2 is a horizontal section thereof, and Fig. 3 is a detail view showing the construction of the individual drills.

Referring to the drawings in detail, A is a cylinder of steel or other suitable material and of any desired size, which is made air-tight by plates B B', secured within and in proximity to each end thereof. Communicating with the exterior of each of the plates B and B' and passing through the air-tight chambers are a plurality of tubes E, which form inlet-pipes for admitting water to the drill-heads F of the drills C, mounted within

said tubes and which are detachably secured at their upper ends to a plate D. Secured to the plate D is a cover G, to which is connected a rod H, by means of which the apparatus may be rotated. J is a mud-drum mounted on the cover G.

As shown in Fig. 3, the raising of the drill-heads F is effected by means of solenoids s s s, fed by the conductor l. Springs f are provided for neutralizing the shock due to the falling of the drill-head and also assisting the drills in rising on the next stroke.

As indicated in the drawings by the arrows, the water before escaping to the bottom of the shaft circulates about each drill, whereby an advantageous cooling of the coils which become heated during operation is obtained. On escaping from the apparatus and rising between the apparatus and the wall of the shaft the circulation of water carries away the small stones, and owing to the sudden reduction of velocity deposits the heavier stones above the mud-drum J, into which they fall. The slime or stones can be removed from the latter without any interference with the operation of the apparatus by means of special devices or can be raised to the surface with the apparatus itself when it becomes necessary to change the drills.

Owing to the great capacity obtained in this way, at a comparatively small cost the apparatus can be used not only for boring shafts under water, but also advantageously employed in sinking shafts in dry or marshy places.

Having thus described our invention, what we claim as new, and desire to secure by Letters Patent, is—

1. In a shaft-boring apparatus, the combination of a rotatable casing, a plurality of drill-containing tubes mounted therein, a drill having an up-and-down stroke mounted in each of said tubes, a tube surrounding each of said drill-containing tubes and forming water-circulating means and operating means carried by each of said drills.

2. In a shaft-boring apparatus, the combination of a rotatable casing, a group of drills carried thereby, mechanism carried by each of said drills to raise the same and springs arranged on each drill and adapted to assist the raising of said drill, substantially as and for the purpose specified.

3. In a shaft-boring apparatus, the combination with a casing constructed as an air vessel and carrying a group of separately-operated drills, essentially as and for the purpose described.
4. In a shaft-boring apparatus, the combination of a rotatable casing, a group of drills carried thereby, mechanism carried by each of said drills to raise the same and spring-operated means mounted on each drill and adapted to assist the said mechanism in rais-

ing each of said drills, substantially as set forth.

In testimony whereof we have hereunto set our hands in presence of two subscribing ¹⁵ witnesses.

EDUARD FRIEH.
RUDOLF NÖLLENBURG.
